UNITED STATES PATENT OFFICE.

CHARLES S. GERRITSON, OF BOSTON, MASSACHUSETTS.

DESIGN FOR A LAMP STAND OR HOLDER.

SPECIFICATION forming part of Design No. 28,804, dated June 7, 1898.

Application filed September 30, 1897. Serial No. 653,648. Term of patent 7 years.

To all whom it may concern:

Be it known that I, CHARLES S. GERRITSON, a citizen of the United States, residing at Boston, county of Suffolk, State of Massachusetts, 5 have invented and produced a new and useful Design for a Lamp Stand or Holder, of which the following is a specification.

A represents the guns, which are arranged together so as to form a stack of guns.

10 B denotes the base of my design, which is made to represent the ground and in a rectangular form, upon which the butt-end of the guns rest, as shown.

C represents bayonets affixed to the end of 15 the muskets.

D denotes a common army cooking-pot supported by the top end of the army-guns.

d represents the legs, and d' the manipulating-handle, of the pot.

20 E denotes a lamp the body of which enters

the pot-chamber and is efficiently supported by the pot.

F represents a canteen resting upon the ground base, G an ordinary army-pistol, and H a knapsack resting upon the base. ²⁵

The leading feature of my design consists in a stack of guns, bayonets affixed thereto, the butt-end of the guns resting on a ground base, the base, a canteen, army-pistol, and knapsack resting on and about the ground base and the guns, an army cooking-pot supported by the stack of guns, and a lamp supported by the cooking-pot. ³⁰

Having described my invention, I claim—

The design for a lamp stand or holder as 35 herein shown and described.

CHARLES S. GERRITSON.
